ATTORNEY5.

UNITED STATES PATENT OFFICE.

ADOLPH STORM, OF MINNEAPOLIS, MINNESOTA.

BEARING-REPLACEMENT APPARATUS.

Application filed December 18, 1922. Serial No. 607,914.

To all whom it may concern:

Be it known that I, ADOLPH STORM, a citizen of the United States, residing at Minneapolis, in the county of Hennepin, State of Minnesota, have invented certain new and useful Improvements in Bearing- Replacement Apparatus; and I do hereby declare the following to be a full, clear, and exact description of the invention, such as will enable others skilled in the art to which it appertains to make and use the same.

The object of the invention is to provide a simple and efficient mechanism for use in rebabbitting and boring bearings and especially the main shaft bearings of a motor or engine, by the use of which the metal designed to constitute the bushing or bearing surface may be poured and accurately bored to fit the shaft in what may be considered a single operation. Further objects are to provide improved means for positioning the elements in connection with which the pouring and boring operations are conducted, so as to secure an accurate alignment with respect to the cam shaft bearings, and means for maintaining the said elements in such position against accidental displacement during the pouring and boring operations. With these general objects in view the invention consists in a construction, combination and relation of parts of which a preferred embodiment is shown in the accompanying drawings, wherein:

Figure 1 is a view of the apparatus applied to an inverted motor bed or block with the pouring or babbitt positioning element in operative position.

Figure 2 is a plan view, partly broken away, of the same with the alternate or interchangeable boring element in position.

Figure 3 is an end view to show more particularly the means whereby the jig or frame is positioned upon and held in proper relation with the exposed surface of the motor bed or block so as to insure an accurate centering of the interchangeable babbitting and boring bars in the main shaft bearings.

Figure 4 is a detail view enlarged of the means for positioning the babbitt metal in the bearing, prior to the removal of the surplus materials serving to allow for shrinkage in the cooling thereof.

Figure 5 is a similar view to illustrate a

convenient method whereby the surplus bushing material may be removed.

Figure 6 is a detail view of one of the cutters carried by the boring bar.

Figure 7 is an enlarged detail view of one of the cutter heads disposed in operative relation with the bore of the bushing to illustrate the method of operation thereof in removing the surplus material of the bushing to effect an accurate fit thereof to the main shaft of the motor.

Essentially the apparatus consists of a jig or frame 10 of a form and size adapting it to rest upon, in substantially coextensive relation with, the normally under surface of an inverted motor bed or block indicated at 11, and having seats or bearings 12 for the alternative reception of the interchangeable babbitting and boring bars 13 and 14 for the purpose of positioning said bars in concentric relations with the shaft bearings 15 of the motor bed or block. The jig or frame 10 has aligning means, consisting of spaced lugs 16 adapted for arrangement in straddling relation with an aligning arbor 17 fitted temporarily in the cam shaft bearing holes 18 of the motor bed or block and serving to determine and maintain the proper relation of the jig or frame to the bed or block. The construction of the aligning device, as will be noted, is such as to permit the engagement thereof with the arbor 17 by a transverse or seating movement of the jig or frame 10 upon the surface of the bed or block, and the removal thereof with equal facility, so as to economize in time and labor.

The babbitting bar preferably carries a plurality of pouring funnels or troughs, corresponding in number with the bearings to be treated, as for example three as indicated in the drawing and commonly used in this connection, each funnel or trough consisting of spaced collars 19 constituting the end walls of the funnel or trough and adjustable upon the bar 13 to occupy positions in close relation with the ends of the shaft bearing 15 to be babbitted, and side walls 20 consisting of plates disposed in parallelism with the axis of the bearing and in upwardly divergent planes with their extremities attached to the collars 19, as by having the ends thereof fitted adjustably in kerfs or slots 21 so that a sufficient range of adjust-

ment of the collars may be afforded to adapt the funnel or trough to bearings of different lengths, while maintaining the proper relation between the end and side walls of 5 the funnel.

Having positioned the parts as indicated the molten metal, either babbitt or its equivalent, designed for use as the bushing material, may be poured until an excess thereof 10 occupies the funnel or trough above the plane of the surface of the half bearing which is being treated, to afford a surplus to allow for the shrinkage of the metal as it cools, and after the temperature has been 15 sufficiently reduced, the side walls of the trough or funnel may be removed as indicated in Figure 5 and the surplus or projecting portions of the bushing material removed as by the operation of a punch and 20 hammer as indicated in Figure 5.

The babbitting bar being of under size as compared with the main or drive shaft for which the bearings are designed, the surplus material at the inner surface of the 25 rough bushing thus formed should then be removed by boring, for which purpose the boring bar 14 should be substituted for the babbitting bar, without alteration in the position of the jig or frame, said boring bar 30 carrying double headed or double ended cutters 22 of a length accurately corresponding with the diameter of the shaft to be fitted in the bearings and held in place for example by a key 23. The heads of the cutter are preferably of a double faced type having a forward cutting or shearing edge 24 which is ground with the proper lead or clearance with reference to the faces 25 and 26 to cut easily and shear off the bulk of the 35 metal as indicated in Figure 7 at 27, while the cutting edge 28 is preferably finished to a size to remove only about eight or ten one-thousandths of an inch as indicated in Figure 7 at 29. No lead or clearance is necessary with reference to the cutting edge 30, 40 the same being ground to the radius or diameter of the finished bearing so as to cut true to the exact size of the proposed bearing. These cutting edges when necessary 45 may be ground across the front faces 31 and on the leading faces 25 and 26 without in any way altering their length or the size of the cut and hence the gage of the bearing 50 which is the ultimate product of the boring 55 operation. It will be noted moreover that the dressing or finishing of the bearing surface both as to the operation of the forward cutting or shearing edge 24 and the finishing edge 28 is accomplished by the definite boring 60 out of the metal as with a boring cutter, in contradistinction to scraping or removing the material by a radial cut, as a means of avoiding side strain and chattering.

What is claimed is:

65 1. A bearing replacement apparatus hav-

ing a jig or frame provided with bearings or seats and a bar supported in said bearings or seats, the frame having an aligning means for engagement with an arbor disposed in the cam shaft bearing holes of a motor bed 70 or block.

2. A bearing replacement apparatus having a jig or frame provided with bearings or seats and a bar supported in said bearings or seats, the frame having aligning 75 means consisting of a pair of spaced lugs for straddling engagement with an arbor disposed in the cam shaft bearing holes of a motor bed or block.

3. A bearing replacement apparatus having a jig or frame provided with bearings or seats, and a bar supported in said bearings or seats, the frame having aligning means for transverse seating engagement with an arbor disposed in the cam shaft 80 bearing holes of a motor bed or block.

4. A bearing replacement apparatus for motors, having a jig or frame for substantially coextensive seating engagement with the under surface of a motor bed or block 85 and carrying a bar in axial relation with the several main bearing members thereof.

5. A bearing replacement apparatus for motors having a jig or frame for substantially coextensive seating engagement with 90 the under surface of a motor bed or block and carrying bearings in registration with the main bearing members of the bed or block, and a bar supported in said bearings.

6. A main bearing replacement apparatus 100 for motors having a jig or frame and a babbitting bar for axial position in a bearing and carrying a pouring trough consisting of end walls and removable side walls.

7. A main bearing replacement apparatus 105 for motors having a jig or frame and a babbitting bar positioned in a bearing and carrying a pouring trough or funnel consisting of end walls and removable upwardly divergent side walls.

8. A main bearing replacement apparatus 110 for motors having a jig or frame and a babbitting bar positioned in a bearing and carrying a pouring trough or funnel consisting of end walls and removable upwardly divergent side walls terminally supported by the end walls.

9. A main bearing replacement apparatus 115 for motors having a jig or frame provided with a babbitting bar positioned in a bearing and carrying a pouring trough or funnel consisting of end walls and removable upwardly divergent side walls terminally supported by the end walls, the end walls being adjustable longitudinally of the bar 120 and having a telescoping relation with the side walls.

10. A bearing replacement apparatus having a jig or frame and a babbitting bar carried thereby and provided with spaced trans- 125

verse collars and interposed longitudinal plates forming a pouring trough or funnel.

11. A bearing replacement apparatus having a jig or frame and a babbittting bar carried thereby and fitted with adjustable collars and intermediate longitudinal plates forming a pouring funnel or trough.

12. A bearing replacement apparatus having a jig or frame and a babbittting bar carried thereby and fitted with collars having kerfs and intermediate longitudinal plates having their end edges fitting in the kerfs.

13. A bearing replacement apparatus having a jig or frame and a babbittting bar carried thereby and provided with a pouring trough consisting of tangentially slotted collars and side plates terminally fitted in the slots of the collars. ¹⁵

In testimony whereof, I affix my signature, in the presence of two witnesses:

ADOLPH STORM.
